UNITED STATES PATENT OFFICE.

JOHN SCHWEIKART, OF DETROIT, MICHIGAN.

ICE-CUTTER.

SPECIFICATION forming part of Letters Patent No. 678,285, dated July 9, 1901.

Application filed January 28, 1901. Serial No. 45,077. (No model.)

To all whom it may concern:

Be it known that I, JOHN SCHWEIKART, a citizen of the United States, residing at Detroit, in the county of Wayne and State of Michigan, have invented certain new and useful Improvements in Ice-Cutters, of which the following is a specification, reference being had therein to the accompanying drawings.

The invention relates to a tool for cutting ice particularly designed for use in trimming off the uneven upper surface or edges of ice cakes which have been deposited in ice-houses to permit of another layer of ice cakes being placed evenly thereon.

15 The invention consists in the novel construction of the ice-cutter and in the peculiar arrangement and combination of its various parts, as will be more fully hereinafter set forth, and pointed out in the claims.

20 In the drawings, Figure 1 is a perspective view of the tool. Fig. 2 is a side elevation thereof; and Fig. 3 is a cross-section taken on line xx , Fig. 2.

In construction the tool comprises a body portion A, composed of a series of parallel and spaced bars, such as B, and a handle C for and connected to the body.

The bars described are formed of metal, and the bar ends at one end of the body are beveled, as shown, forming cutting-points, such as a . Each bar is also apertured in proximity to each of its ends, and the several bars are separated one from another by means of spacing-thimbles D, interposed between the bars and registering with the apertures therein at each end, as plainly shown in Fig. 1. The bars are clamped together by means of bolts E, which extend through the apertures and thimbles.

40 The handle referred to is preferably yoke-shaped in configuration, the end portions embracing the tool-body and having a pivotal connection with the latter at substantially the center. The pivots b extend through suitable eyes c in the handle ends and are fixed to the outer bars of the body.

By forming a pivotal connection between the handle and body the latter when being operated normally guides itself, so that the 45 smoothing or planing of the ice cakes is readily effected. Also in addition to removing

obstructions presented by the uneven edges of the cakes it corrugates the upper surfaces, so that air-spaces will be formed between the two layers of ice, preventing the cakes from 55 freezing together.

In constructing the cutter I preferably form cutting-points a' at the rear end of the tool by beveling the ends of the bars in a manner similar to that described, but forming the 60 bevels in the opposite direction. Thus I am enabled when one set of cutting-points becomes dull from use to reverse the tool and obtain a new set of points; also I have provided means whereby when necessary the tool-body 65 may be tilted either up or down for the purpose of more effectively cutting the ice. These means consist, essentially, of pins e , detachably secured to the outer bars of the body to one side of the handle-pivot, and 70 links f , engaging the pins described and having a pivotal connection with the handle. As shown, the links are slotted, forming what are generally termed "lost-motion" links, to allow of a limited play of the handle relative 75 to the body during the planing or cutting. The pins referred to extend through apertures in the bars, as indicated, and are held in place by split keys, such as g .

When it is desired to reverse the tool, the 80 link-pins are withdrawn from the body, the latter reversed, and the pins again inserted in the outer bars in apertures h , formed in the body for this purpose, the pins being then locked in place, as described.

85 It will be obvious from the description of the tilting mechanism that the raising or lowering of the tool is effected by lifting or pressing down upon the handle beyond the limit of lost motion.

90 What I claim as my invention is—

1. In a tool for trimming ice, the combination with the tool-body comprising a series of spaced and connected bars having cutting-points formed thereon at one end of the body, 95 and a handle having a pivotal connection adapted to permit limited play with said body.

2. In a tool for trimming ice, the combination of the tool-body comprising a series of thin parallelly-arranged bars spaced from 100 and connected to each other, the opposite ends of each bar being beveled to form cut-

ting-points thereon, and a handle pivotally connected to the body, substantially as described.

3. In a tool for trimming ice, the combination of the tool-body comprising a series of parallel bars spaced from each other and apertured in proximity to their ends, spacing-thimbles intermediate the bars and registering with the apertures therein, securing-bolts extending through said bars and thimbles, a handle pivotally connected to the body, pins

detachably connected to the body to one side of the handle-pivots, and slotted links carried by the handle and engaging the pins, substantially as described.

In testimony whereof I affix my signature in presence of two witnesses.

JOHN SCHWEIKART. 15
